(57) **CLAIM**

We claim the ornamental design for an combined audio and visual conferencing device, as shown and described.

DESCRIPTION

FIG. 1 is a front, top perspective view of an combined audio and visual conferencing device.

FIG. 2 is a front elevational view thereof, the rear elevational view thereof being a mirror image.

FIG. 3 is a right-side elevational view thereof, the left-side elevational view thereof being a mirror image; and,

FIG. 4 is a top plan view thereof.

The bottom of the combined audio and visual conferencing device, not shown, forms no part of the claimed design. Broken lines in the drawings form no part of the claimed design.

1 Claim, 2 Drawing Sheets
